United States Patent Office

Des. 221,418

Patented Aug. 17, 1971

221,418

PACKAGING CUP

Alfred W. Kinney, Kansas City, Mo., assignor to Phillips Petroleum Company

Filed Feb. 5, 1970, Ser. No. 21,291

Term of patent 14 years

Int. Cl. D9—99

U.S. Cl. D9—220

FIG. 3

FIG. 1

FIG. 1 is a perspective view of a packaging cup showing my new design;

FIG. 2 is an enlarged, vertical cross-sectional view of the left-hand portion of the packaging cup of FIG. 1, the view of the right-hand portion being a mirror image thereof; and

FIG. 3 is a bottom plan view of the packaging cup of FIG. 1.

I claim:

The ornamental design for a packaging cup, as shown and described.
